UNITED STATES PATENT OFFICE.

LORENZO BREE, OF CHICAGO, ILLINOIS, ASSIGNOR TO ROBERT P. DUNSTON, OF HANCOCK, MICHIGAN.

EXCAVATING APPARATUS.

No. 895,236.

Specification of Letters Patent.

Patented Aug. 4, 1908.

Application filed October 19, 1906. Serial No. 339,619.

To all whom it may concern:

Be it known that I, LORENZO BREE, a citizen of the United States, residing at Chicago, in the county of Cook and State of Illinois, have invented a certain new and useful Improvement in Excavating Apparatus, of which the following is a specification.

My invention relates to excavating machines and has for its object in particular to improve the form of bucket, its mode of delivery and the disposition of the spoils brought up by the buckets.

The invention has for a further object such new and improved constructions in apparatus of this character as are set forth in the following specification.

My invention is illustrated in the accompanying drawings as applied to a wheel ditching machine comprising a carriage, a swinging frame at the end of the carriage, and a rotating excavating wheel mounted on the swinging frame. As my invention relates only to the digging element, together with the devices for the disposition of the spoils, I have shown only the rear end of such machine, this being sufficient to illustrate the operation of the device.

Figure 1 is a side view of the excavating wheel, and Fig. 2, a vertical section taken on line 2—2 of Fig. 1.

Like letters of reference indicate like parts in all the drawings.

From the rear of the carriage extend a pair of beams, one of which is shown at A, these being supported by wheels B. On the beams are standards C having bearings for the shaft C' on which is mounted the swinging frame D, the position of which is controlled by the cable D¹ connected with any suitable windlass (not here shown.) On the frame D are the bearings D² D² in which turns the hollow shaft E. The hub F of the excavating wheel is rigidly secured to this shaft by the key F⁵.

G, G are collars interposed between the bearings and the hub.

F¹ is the rim of the wheel which is preferably of channel iron construction and has the peripheral teeth F² for the drive chain.

F³ are the spokes secured to the channel iron F¹ and to the flanges F⁴ F⁴ on the hub.

The wheel is driven by a chain H extending over a sprocket H¹ on the shaft C, this shaft carrying also the sprocket H² driven by a chain H³ connected with any suitable motor on the carriage.

It will be understood that the construction of the wheel and the arrangement of the driving device might be very greatly varied.

The buckets are preferably located peripherally and at each side of the wheel in alternate arrangement, designated generally by the letters J. They may be secured to the wheel in any desired manner, for example, by the braces or straps J¹, J² at the rear and front respectively of the buckets. The buckets are provided preferably with the digging lips J³. The buckets are arranged to discharge laterally and from the top of the wheel, and suitable conveyers are arranged to receive the spoils as they come from the bucket and carry them to the sides of the trench. With this in view the buckets are formed with hinged doors preferably comprising the whole of the inner side of the bucket, that is, the side adjacent to the wheel. I have shown the bodies of the buckets provided with lugs J⁴ to which are hinged the doors J⁵ provided with similar lugs J⁶. The hinges are arranged on the side of the bucket nearer the central plane of the wheel so that the doors, when they are released, form slides which conduct the material to one or other of the conveyers arranged on opposite sides of the wheel. The doors may be released by any suitable mechanism, preferably automatic. I have shown them held or locked by a bell crank latch K pivoted to the inside of the bucket at K¹ and having the right-angle extension K² which is designed to stand in the path of a stationary portion of the machine and be tripped thereby through the rotation of the excavating wheel. The latch has the notched end K³ which extends through a slot K⁴ in the door or swinging side of the bucket. A spring K⁵ retracts the latch to its normal position.

To receive the material discharged from the buckets I provide preferably belt conveyers or aprons L, L, one at each side of the wheel. These conveyers are supported by a frame work carried by a shaft L¹ extending through the hollow shaft E. At each end of the shaft L¹ is a collar L² to which is secured a V-shaped brace L³, the ends of which carry the upright supports L⁴, L⁴. The connections between L³ and L⁴ are adjustable by means of the perforations L⁵, L⁵. To the upper ends of the uprights L⁴ L⁴ are pivoted the oblique strips L⁶, L⁶ supported at their inner ends by the supports L⁷, L⁷ secured to

suitable collars L^8 , L^9 on the shaft L^1 . A tie-rod L^9 is pivoted on the swinging frame D at L^{10} and is screw threaded at the other end which extends through one of the supports L^7 to which it is adjustably connected by means of the jam nuts L^{11} , L^{12} . The frame work on each side of the wheel formed by L^5 , L^6 and L^7 supports the conveyer or the apron L which runs over a roller L^{12} journaled in the ends of the uprights L^4 and over a roller L^{13} journaled in the side pieces L^{14} . These side pieces are connected by the oblique platform L^{15} preferably provided with the upturned flanges L^{16} which form a sort of trough in which the apron runs. The apron may be operated by gravity or may be driven by any suitable apparatus. If the conveyer operates by gravity it is advisable in certain classes of heavy, sticky soils to increase the slant of the conveyer. I have shown means for doing this in the cams M on the wheel which cams engage with the roller L^{17} on the frame L^{18} secured to the side pieces L^{14} . This operation is so timed that after the bucket has discharged its load upon the conveyer one of the cams engages with the roller and tilts the upper end of the conveyer so as to give added inclination thereto. The flanges L^{16} serve to trip the latches K on the buckets.

I wish it to be understood that I do not desire to be limited to the exact details of construction shown and described for obvious modifications will occur to any one skilled in the art.

The use and operation of my device will perhaps have been made sufficiently clear by the foregoing description. To recapitulate, it will be understood that the wheel is first set in motion through the agency of the chains H^3 , H , the rotation being from left to right in Fig. 1. The buckets will scoop out a trench of the desired depth, this being regulated by the angular position of the frame D . As the buckets get to the top of the wheel their inner sides are released and the load discharged upon one of the conveyers L , L . This discharge from the top of the wheel has some importance, particularly in digging a deep trench where the wheel may be working nearly, if not quite, hub deep. There is little, if any chance that the buckets will become clogged in an arrangement of this sort. The packing naturally occurs between the sides of the bucket, and when one of these is released the pressure is at once taken away and the contents of the bucket discharged. Moreover, this discharge is almost vertical and upon a conveyer which is at a sufficient height from the ground to insure the proper piling of the spoils at the sides of the trench. As the buckets are inverted the door swings

back into place and is automatically latched. The conveyers and their supporting frame work can, of course, be set to a proper position on the supporting shaft in accordance with the angular position of the frame D which latter will depend upon the depth of the trench being dug.

I claim:

1. In an excavating machine, the combination of an excavating wheel, an apron at the side thereof to receive the spoils, and an excavating bucket having a discharge opening controlled by a door and adapted to discharge the contents of the bucket onto said apron.

2. In an excavating machine, the combination of an excavating wheel, a gravity apron at the side thereof to receive the spoils, and an excavating bucket having a discharge opening controlled by a door and adapted to discharge the contents of the bucket onto said apron.

3. In an excavating machine, the combination of an excavating wheel, a gravity apron at the side thereof to receive the spoils, an excavating bucket having a discharge opening controlled by a door and adapted to discharge the contents of the bucket onto said apron, and means for increasing the slant of said apron.

4. In an excavating machine, the combination of an excavating wheel, a gravity apron at the side thereof to receive the spoils, an excavating bucket having a discharge opening controlled by a door and adapted to discharge the contents of the bucket onto said apron, and means for intermittently lifting the upper end of said apron.

5. In an excavating machine, the combination of an excavating wheel, a gravity apron at the side thereof to receive the spoils, an excavating bucket having a discharge opening controlled by a door and adapted to discharge the contents of the bucket onto said apron, and means for intermittently lifting the upper end of said apron comprising a cam on said excavating wheel.

6. In an excavating machine, an excavating bucket open at the top and normally closed at the sides and bottom and having a door on one side thereof with means for opening the door.

7. In an excavating machine, an excavating bucket open at the top and normally closed at the sides and bottom and having a hinged door on one side thereof with a latch to hold said door closed, and means for releasing said latch.

LORENZO BREE.
